(57) **CLAIM**

The ornamental design for a combination gun rest and shoulder strap, as shown and described.

DESCRIPTION

FIG. 1 is a front view of the gun rest illustrating the novel design.

FIG. 2 is a top view of the gun rest of FIG. 1.

FIG. 3 is a rear view of the gun rest of FIG. 1.

FIG. 4 is a bottom view of the gun rest of FIG. 1.

FIG. 5 is a left side view of the gun rest of FIG. 1.

FIG. 6 is a right side view of the gun rest of FIG. 1.

FIG. 7 is a front top left perspective view of the gun rest of FIG. 1.

FIG. 8 is a rear top right perspective view of the gun rest of FIG. 1.

FIG. 9 is a front view of the shoulder strap for the gun rest of FIG. 1.

FIG. 10 is a rear view of the shoulder strap for the gun rest of FIG. 1.

FIG. 11 is a front view of the gun rest of FIG. 1 and the shoulder strap in FIG. 9 as they would be used together.

FIG. 12 is a front left perspective view of the combination gun rest of FIG. 1 and the shoulder strap of FIG. 9 as they would be used together. The broken line showings of surfaces of the claimed design represent stitching and forms a part of the claimed invention; and,

FIG. 13 is a rear view of the combination gun rest of FIG. 1 and the shoulder strap of FIG. 9 as they would be used together showing a long gun as it would be placed in the gun rest of FIG. 1. The broken line showings of an exemplary rifle in FIG. 13 illustrates environment which does not form a part of the claimed design.
